[57] CLAIM

The ornamental design for a combined reservoir and
wheeled base assembly for a vacuum cleaner, as shown
and described.

DESCRIPTION

FIG. 1 is a perspective view of a combined reservoir
and wheeled base assembly for a vacuum cleaner showing
my new design with the clamp on the near side
being in closed position and the clamp on the opposing
side being in open position;

FIG. 2 is a top plan view thereof;

FIG. 3 is a front end elevational view thereof, the rear
end being a mirror image;

FIG. 4 is a side elevational view thereof with the clamps
in closed position, the opposite side being a mirror im-
age; and,

FIG. 5 is a bottom plan view thereof.

*Fig. 1.**Fig. 2.*
